(57) **CLAIM**

The ornamental design for clock radio with docking station, as shown and described.

DESCRIPTION

FIG. 1 is a perspective view of a clock radio with docking station, according to my new design;

FIG. 2 is a front elevational view of the clock radio with docking station of FIG. 1;

FIG. 3 is a rear elevational view of the clock radio with docking station of FIG. 1;

FIG. 4 is a left elevational view of the clock radio with docking station of FIG. 1;

FIG. 5 is a right elevational view of the clock radio with docking station of FIG. 1;

FIG. 6 is a top elevational view of the clock radio with docking station of FIG. 1; and,

FIG. 7 is a bottom elevational view of the clock radio with docking station of FIG. 1.

The features shown in broken lines are environment only and not part of the claimed design.
